UNITED STATES PATENT OFFICE.

CHARLES A. BAXTER, OF WEST LINN, OREGON.

STEAM-REMOVING MEANS FOR PAPER-PULP GRINDERS.

Application filed August 23, 1922. Serial No. 583,796.

To all whom it may concern:

Be it known that I, CHARLES A. BAXTER, a citizen of the United States, and a resident of West Linn, county of Clackamas, and State of Oregon, have invented new and useful Improvements in Steam-Removing Means for Paper-Pulp Grinders, of which the following is a specification.

My invention relates to means for confining and carrying off the vapors generated by operating devices, such for example, as grinding devices. Specifically my invention relates to paper pulp grinders. In the operation of the latter a large volume of steam is generated which renders the room hazardous as well as uncomfortable to the workmen; and besides, since the building is generally built of lumber, this steam has a tendency to cause undue rotting of the building.

Many and varied attempts have been made to remove this steam, but as easy access must be had to the mechanism of the grinder, a housing has been impractical. It is necessary that one end of the grinder be left open so that the grindstones can be jiggled, that is, to have the surface roughened so that the stone will work effectively. The casing also is not airtight, and canopies and the like which have been placed over this open side have not only interfered with the correct operation of the machine, but also have been ineffectual inasmuch as enough steam escapes from the cracks to render these devices valueless.

The object of my invention is to provide simple and efficient means for confining and carrying off said steam. The pulp grinder usually comprises a grind-stone about which are radially disposed a plurality of devices for holding the blocks of wood to be ground into pulp on the grind-stone. All these devices are housed by a casing having doors giving access to said devices for holding the blocks of wood, and the casing is left open at one side so as to give access to the grind stone for the purpose of "jigging" the same.

I attain my object by covering said open side of the main housing by a supplemental removable, hood-like, housing section, enclosing a substantial space constituting a chamber with which the other section is connected by passageway extending around the parts of the pulp grinder. To the chamber are connected means for creating a draft, thereby converting the spaces within the

chamber into a region of negative pressure; consequently air rushes through the devices about the doors into said chamber, and is moved from the latter by said draft creating means, to the atmosphere.

The walls of the removable housing section at its open side are adapted to abut closely with said walls at the open end of said main housing section, and the supplemental housing section is made of substantial mass, so that by its weight it will resist inadvertent displacement from such abutment, and does not require device for fastening it to the main section of the housing. For said draft creating means I prefer to provide a conduit leading from the said removable housing-section to the atmosphere, such conduit being built in two principal sections, one of which is provided on said removable housing section, constituting an integral part thereof; and I provide means for readily connecting, and disconnecting, said conduit sections; the latter means also being adapted to tend to hold said removable housing section in place on its base. It is understood that the main housing is adapted to provide ample air passageways around the parts of the pulp grinder and thence through the open side of said main housing into the chamber of said supplemental housing.

The details of the above mentioned features are hereinafter fully described with reference to—

Fig. 1 shows a diagrammatic elevation of a paper mill grinder with my supplemental housing section in place, and illustrates how the latter is removably connected to a draught creating conduit leading to the atmosphere; and

Fig. 2 is a perspective detail of my supplemental housing section and of that section of said conduit provided thereon.

My supplemental housing section is adapted to be fitted to a standard paper pulp grinder housing, mounted on a foundation *b* which encloses a grinding roll *c* which rotates on the shaft *d*. A block of wood *e* is held against the periphery of this grindstone by one of a series of hydraulic presses *f* and the friction between the stone and the block of wood grinds small fibres from the block which are deposited in the bottom of the casing. A stream of water flows continuously over the face of the grindstone and the block and the friction between the

wheel and the block generates enough heat to vaporize part of this water which tends to escape to the atmosphere. The only large opening in the main housing is the open side 5 a' thru which access is had to the grind stone. My supplemental housing section g is adapted to fit snugly around this open side and also to seat firmly on the extension b' of the foundation b and thereby to provide 10 a substantially airtight connection therewith. The housing section g has an integral conduit section i which has a rounded top j and a lateral flange k . A horizontal header pipe n is connected to a stack or a 15 mechanical means for producing a partial vacuum in the pipe, such for example as the fan o , shown in Fig. 1.

This horizontal header n can be connected to a series of grinders and thus the steam can all be removed by the same stack, or by the same mechanical means. It has been found by experimentation that the steam generated creates enough difference in pressure so that it will rise without external aid. 20 It has also been found that the steam passing thru these headers and connection pipes gives off enough heat to the grinder room so as to eliminate the necessity of providing other heating devices for the comfort of the workmen. 25

Mechanical means such as the fan o can be provided to accelerate the removal of the steam, but in either case the removing means causes a region of negative pressure in the 30 header and the air inside of the housing section g and the main housing a of the pulp grinder. This causes the grinding process to be carried on under a decreased pressure and as the outlet for the steam and air is larger than the summation of the orifices the generated steam is prevented from passing out thru the orifices in the grinder casing except thru the open side a' , and thus effectively carries away all of the vapors generated. 40

A loose rotatable slip joint m is connected to the conduit section l and is adapted to fit over the section j and normally to rest on the lateral flange k thus connecting the integral section i to the section l . When it is desired, however, to remove the supplemental housing section g from the main housing a it is necessary to lift this slip joint, and the section g can be lifted out of position. 50 And to replace, it is merely necessary to seat the section g on the foundation b' and adjust the edges g' to the casing a and then pass the slip joint over the section j and allow it to seat on the flange k . 55

I claim:

1. In combination with the housing of an operating device of the character described, such housing having crevices in its walls and a relatively large opening at one side, of a supplemental removable housing section, 60

open at one side in correspondence with said side opening of the main housing, and adapted to have its walls placed in abutment with the walls of the latter, thereby to enclose a space constituting a chamber of substantial dimensions; means for creating a draft from said chamber to the atmosphere, thereby creating a region of negative pressure in said chamber tending to draw in exterior air through said orifices of the main housing; such means adapted to be connected with and disconnected from said supplemental housing section, thereby to permit the removal of the latter. 70

2. In combination with the housing of an operating device of the character described, such housing having crevices in the walls and a relatively large opening at one side, of a supplemental removable housing section, open at one side in correspondence with said side opening of the main housing, and adapted to have its walls placed in abutment with the walls of the latter, thereby to enclose a space constituting a chamber of substantial dimensions; means for creating a draft from said chamber to the atmosphere, thereby creating a region of negative pressure in said chamber tending to draw in exterior air through said orifices of the main housing; such means adapted to be connected with and disconnected from said supplemental housing section, thereby to permit the removal of the latter. 75

3. In combination with the housing of an operating device of the character described, such housing having crevices in its walls, and a relatively large opening at one side, 80

of a supplemental removable housing section, open at one side in correspondence with said side opening of the main housing, and adapted to have its walls placed in abutment with the walls of the latter, thereby to enclose a space constituting a chamber of substantial dimensions; means for creating a draft from said chamber to the atmosphere, thereby creating a region of negative pressure in said chamber tending to draw in exterior air through said orifices of the main housing; such means adapted to be connected with and disconnected from said supplemental housing section, thereby to permit the removal of the latter. 85

4. In combination with the housing of an operating device of the character described, such housing having crevices in its walls, and a relatively large opening at one side, 90

of a supplemental removable housing section, open at one side in correspondence with said side opening of the main housing, and adapted to have its walls placed in abutment with the walls of the latter, thereby to enclose a space constituting a chamber of substantial dimensions; means for creating a draft from said chamber to the atmosphere, thereby creating a region of negative pressure in said chamber tending to draw in exterior air through said orifices of the main housing; such means adapted to be connected with and disconnected from said supplemental housing section, thereby to permit the removal of the latter. 95

5. In combination with the housing of an operating device of the character described, such housing having crevices in its walls, and a relatively large opening at one side, 100

of a supplemental removable housing section, open at one side in correspondence with said side opening of the main housing, and adapted to have its walls placed in abutment with the walls of the latter, thereby to enclose a space constituting a chamber of substantial dimensions; means for creating a draft from said chamber to the atmosphere, thereby creating a region of negative pressure in said chamber tending to draw in exterior air through said orifices of the main housing; such means adapted to be connected with and disconnected from said supplemental housing section, thereby to permit the removal of the latter. 105

6. In combination with the housing of an operating device of the character described, such housing having crevices in its walls, and a relatively large opening at one side, 110

of a supplemental removable housing section, open at one side in correspondence with said side opening of the main housing, and adapted to have its walls placed in abutment with the walls of the latter, thereby to enclose a space constituting a chamber of substantial dimensions; means for creating a draft from said chamber to the atmosphere, thereby creating a region of negative pressure in said chamber tending to draw in exterior air through said orifices of the main housing; such means adapted to be connected with and disconnected from said supplemental housing section, thereby to permit the removal of the latter. 115

7. In combination with the housing of an operating device of the character described, such housing having crevices in its walls, and a relatively large opening at one side, 120

of a supplemental removable housing section, open at one side in correspondence with said side opening of the main housing, and adapted to have its walls placed in abutment with the walls of the latter, thereby to enclose a space constituting a chamber of substantial dimensions; means for creating a draft from said chamber to the atmosphere, thereby creating a region of negative pressure in said chamber tending to draw in exterior air through said orifices of the main housing; such means adapted to be connected with and disconnected from said supplemental housing section, thereby to permit the removal of the latter. 125

8. In combination with the housing of an operating device of the character described, such housing having crevices in its walls, and a relatively large opening at one side, 130

side, of a supplemental removable housing section, open at one side in correspondence with said side opening of the main housing, and adapted to have its walls placed in abutment with the walls of the latter, thereby to enclose a space constituting a chamber of substantial dimensions; a conduit leading from said chamber to the atmosphere, such conduit comprising a section forming an integral part of said supplemental housing section, and a complementary section; and a slip-collar, mounted on one of said conduit sections, adjustable into and out of engagement with the other conduit section, thereby to permit the removal of said supplemental housing section, said connection of the conduit sections being adapted also to tend to hold said supplemental housing section in place.

20 5. In combination with the housing of an operating device of the character described, such housing having crevices in the

walls and a relatively large opening at one side, of a supplemental removable housing section open at one side in correspondence with said side opening of the main housing, and adapted to have its walls placed in abutment with the walls of the latter, thereby to enclose a space constituting a chamber of substantial dimensions; said supplemental housing section being made of substantial mass so as to tend to resist inadvertent displacement, means for creating a draft from said chamber to the atmosphere, thereby creating a region of negative pressure in said chamber tending to draw in exterior air through said orifices of the main housing; such means adapted to be connected with and disconnected from, said supplemental housing section thereby to permit the removal of the latter, said connection of the conduit sections tending also to hold said supplemental housing section in place.

CHARLES A. BAXTER.
